Primary Examiner — Holly E Thurman*Assistant Examiner* — Altaira J Swangin(74) Attorney, Agent, or Firm — Whitewood Law PLLC(57) CLAIM

What is claimed is an ornamental design for a twin body spice rack, as shown and described.

DESCRIPTION

FIG. 1 is a top left perspective view of a twin body spice rack showing my new design;

FIG. 2 is a right side elevational view thereof;

FIG. 3 is a left side elevational view thereof;

FIG. 4 is a front view thereof;

FIG. 5 is a rear view thereof;

FIG. 6 is a top plan view thereof; and,

FIG. 7 is a bottom plan thereof.

The broken lines shown in all the drawings depict portions of the twin body spice rack that form no part of the claimed design.
